UNITED STATES PATENT OFFICE.

GUSTAV F. ANDERSON, OF BROOKLYN, NEW YORK, ASSIGNOR TO PARAGON CAN & CAP COMPANY, INC., OF BROOKLYN, NEW YORK, A CORPORATION OF NEW YORK.

ART OF MANUFACTURING CLOSURES FOR RECEPTACLES.

Application filed November 2, 1921. Serial No. 512,262.

To all whom it may concern:

Be it known that I, GUSTAV F. ANDERSON, a subject of the King of Sweden, and resident of the borough of Brooklyn, in the city 5 and State of New York, have invented a new and useful Improvement in the Art of Manufacturing Closures for Receptacles, of which the following is a specification.

This invention relates to the art of manufacturing closures for receptacles and the object is to provide an improved method for use in the manufacture of such closures, whereby an interior folded spiral rib may be formed within the body portion of the closure, the method producing a closure which 10 will be very strong and rigid and which will be simple and inexpensive to manufacture.

This method is illustrated and described 20 in connection with a closure of that type in which a blank of the desired shape and size is rolled or bent into tubular form and its adjacent edges seamed together to produce the body portion of the closure, said body portion being combined with a top disk to 25 which it is united by a seam, the said edges of the blank and the top disk being preferably covered or concealed by the said seams.

30 My invention includes the method of producing a folded rib along one face of the blank and bending the blank to cause the folded rib to form an interior spiral thread for the closure.

35 In the accompanying drawings,

Fig. 1 represents the closure in side elevation.

Fig. 2 represents a longitudinal section through the same.

40 Fig. 3 represents a face view of the blank in which the folded rib is formed and from which blank the tubular body portion of the closure is formed.

Fig. 4 represents an edge view of the said blank.

45 Figs. 5, 6, 7, 8 and 9 represent successive steps in the formation of the folded rib.

The top disk of the closure is denoted by 1 and the tubular body portion of the closure by 2. The bottom edge of the body portion may be provided with an exterior bead 50 3, if so desired. The top edge of the tubular body portion 2 and the peripheral edge of the top disk 1 are united by a seam 4 which is preferably of a type which will

cover and conceal the raw edges of the top disk and body portion at this joint. The tubular body portion of the closure is formed from a blank 5, preferably substantially rectangular, of sheet material as, for instance, sheet metal of the desired shape and size bent or rolled into cylindrical form and having its adjacent edges united by a seam 6, which seam is preferably of that type which will cover and conceal the raw edges 60 of the said blank at this joint.

The blank 5 which forms the body portion of the closure is folded between its top and bottom edges by a series of operations, to form a folded rib 7 extending along one 70 face of the blank, which rib preferably extends diagonally from side to side of the blank. This blank is so bent or rolled and its adjacent edges seamed together to form the body portion of the closure, as to cause 75 the folded rib 7 to form a spiral thread 8 around the interior of the body portion of the closure.

The several steps in the formation of the folded rib are illustrated in Figs. 5 to 9 inclusive, it being understood that any instrumentalities of well-known or approved construction may be used for carrying out these steps. The die 9 is provided with an open groove 10. The plunger 11 is arranged 80 to coact with the open groove 10 of the die to exert a lateral pressure on the blank 5 to distort the same into the form shown in Fig. 6. This plunger 11 is provided with oppositely arranged open grooves 12 and 90 13 in different longitudinal planes. Longitudinal members 14 and 15 are arranged to coact with these open grooves 12 and 13 to impart opposite folds to the blank, as shown in Fig. 7. After the plunger 11 has been 95 removed, the still further movement of these members 14 and 15 will complete the longitudinal pressure to force the parts into the position shown in Fig. 8. Members 16 and 17 may then be employed to exert lateral 100 pressure to flatten and complete the folded rib 7, as shown in Fig. 9.

The blank with its folded rib extending along one face thereof may then be folded or rolled and its adjacent edges seamed together to form the tubular body portion. The top disk may then be united to the body portion in the usual manner.

It is evident that the fold illustrated in connection with the rib 7 is only one of 110

many different types of folds which might be used successfully to form the interior folded spiral thread for the closure.

From the above description, it will be seen that by producing a folded rib along one face of the blank and by folding or rolling the blank to produce the body portion of the closure, I am enabled to produce an interiorly screw threaded closure which is very simple and inexpensive to manufacture and one which will be very strong and durable, the internal rib or thread serving as a rigid support for the closure structure and one which will prevent the separation or distortion of the closure.

What I claim is:

1. The art of manufacturing a built-up receptacle closure, comprising providing a blank, folding said blank upon itself to form a rib extending across one face thereof, and so bending said blank to form the body portion of the closure that the rib forms an interior folded screw-thread for the closure.

2. The art of manufacturing a built-up receptacle closure, comprising providing a substantially rectangular blank, folding said blank upon itself to form a rib extending diagonally across one face thereof, and bending said blank to form the body portion of the closure, whereby the rib forms an interior folded screw-thread for the closure.

3. The art of manufacturing a built-up receptacle closure, comprising providing a blank, exerting pressures thereon in different directions to form a folded rib across one face of the blank, and so bending the

blank to form the body portion of the closure that the folded rib will form an interior spiral thread for the closure.

4. The art of manufacturing a built-up receptacle closure, comprising providing a substantially rectangular blank, exerting pressures thereon in different directions to fold said blank to form a rib extending diagonally across one face of the blank, and bending the blank to form the body portion of the closure, whereby the folded rib will form an interior spiral thread for the closure.

5. The art of manufacturing a built-up receptacle closure, comprising providing a blank, exerting successive lateral longitudinal and lateral pressures thereon to form a folded rib across one face of the blank, and so bending the blank to form the body portion of the closure that the folded rib will form an interior spiral thread for the closure.

6. The art of manufacturing a built-up receptacle, comprising providing a substantially rectangular blank, exerting successive lateral longitudinal and lateral pressures thereon to fold said blank to form a rib extending diagonally across one face of the blank, and bending the blank to form the body portion of the closure, whereby the folded rib will form an interior spiral thread for the closure.

In testimony, that I claim the foregoing as my invention, I have signed my name this 22nd day of August 1921.

GUSTAV F. ANDERSON.
